(75) Inventor: **Eric Bradley Petschek**, Fort Collins, CO (US)

* cited by examiner

(73) Assignee: **Tepsin's, LLC.**, Windsor, CO (US)

Primary Examiner—Nelson C. Holtje
(74) Attorney, Agent, or Firm—Ancel W. Lewis, Jr.

(**) Term: **14 Years**

(57) **CLAIM**

(21) Appl. No.: **29/162,743**

The ornamental design for an insulated cover for sprinkler backflow assembly/valves, as shown and described.

(22) Filed: **Jun. 20, 2002**

DESCRIPTION

(51) LOC (7) Cl. **23-01**

(52) U.S. Cl. **D23/249**

(58) Field of Search D23/249; 239/397.5;
D9/305; 137/341, 375, 382, 312

FIG. 1 is a right side elevation view of an insulated cover for sprinkler valves particularly suited for back flow valves showing my new design, the left side elevation view being a mirror image of that shown;

FIG. 2 is a top plan view thereof;

FIG. 3 is a bottom plan view thereof;

FIG. 4 is a left end elevation view thereof, the right end elevation view being a mirror image of that shown; and,

FIG. 5 is a top left end perspective view thereof, the broken line disclosure being a sprinkler backflow assembly for illustrative purposes only and forming no part of the claimed invention.
